(57) CLAIM

The ornamental design for a stamp, as shown and described.

DESCRIPTION

FIG. 1 is a front perspective view of a stamp showing my new design;

FIG. 2 is a front view thereof;

FIG. 3 is a rear view thereof;

FIG. 4 is a left view thereof;

FIG. 5 is a right view thereof; and,

FIG. 6 is a rear perspective view thereof.

The broken lines in the figure drawings are shown for illustrative purposes only and form no part of the claimed design.
